UNITED STATES PATENT OFFICE.

JOHN A. MORRISON, OF MANSFIELD, OHIO.

LIFTING JACK.

Application filed February 21, 1921. Serial No. 446,713.

To all whom it may concern:

Be it known that I, JOHN A. MORRISON, a citizen of the United States, residing at Mansfield, in the county of Richland and State of Ohio, have invented a new and useful Lifting Jack, of which the following is a specification.

This invention relates to lifting jacks and more particularly to that type of jack especially adapted for automobile use, and is an improvement over my allowed application for improvement in lifting jacks, Serial No. 369,826, filed March 29, 1920.

The objects of the present invention are to provide a jack of the character illustrated and described in my prior application above referred to in which a two part lifting bar is provided, one part being arranged to be raised independently of the other part to a predetermined height after which the two parts are automatically locked together and raised to the maximum height, means being provided for positively preventing one part of the lifting bar from being moved until the other part has reached a predetermined height, other objects being to generally improve and simplify the construction of lifting jacks of this general character.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims, without departing from the spirit or sacrificing any of the advantages of the invention.

The invention thus set forth in general terms is illustrated in the accompanying drawings forming part hereof in which—

Figure 1 is a side elevation of a lifting jack embodying the invention showing the lifting bar in lowered position, a part of the gear housing being broken away for the purpose of illustration.

Fig. 2 is a front elevation of the same.

Fig. 3 is a section on the line 3—3, Fig. 2.

Fig. 4 is a section on the line 4—4, Fig. 3.

Fig. 5 is a front view of the jack with the housing broken away, the driving worm being shown in section.

Fig. 6 is a top plan view of the jack.

Fig. 7 is a section similar to Fig. 3, showing the lifting bar in the raised position.

Fig. 8 is a section similar to Fig. 4, showing the lifting bar in the raised position.

Fig. 9 is a detached perspective view of the channel member of the lifting bar.

Fig. 10 is a similar view of the rack bar member of the lifting bar, and

Fig. 11 is a detail perspective view upon a larger scale of the locking key, by means of which the two members of the lifting bar are automatically locked together.

A practical embodiment of the invention is disclosed in the accompanying drawings forming a part of this specification in which similar numerals of reference indicate corresponding parts throughout the several views.

The standard within which the lifting mechanism is carried comprises a housing 1, the lower portion of which is preferably skirted as shown at 2 to provide a more stable support for the jack, the base of the housing being closed as shown at 3 to prevent dirt and dust from entering the housing and coming into contact with the working parts of the jack.

The lifting bar of the jack comprises two members, a channel shaped rack member 4 being vertically slidably mounted within the housing and provided with a T-shaped vertical slot 5 within which is slidably mounted the T-shaped rack bar 6, the bar 6 being normally telescoped within the channel member 4 when the jack is in the lowered position as shown in Figs. 1 to 5 inclusive.

In this position the teeth of the rack bar 6 meshes with the teeth of the pinion 7, which pinion is of substantially the width of the channel bar 4 and is fixed upon the shaft 8 upon which shaft is also fixed the worm gear 9 meshing with the worm 10, a suitable gear housing 11 being provided to accommodate the worm gear and worm.

The upper end portion of the rack channel 100 is provided with the cut-out portion 7a within which the pinion 7 is located when the rack channel is in the lowered position, the pinion thus being normally out of mesh with the teeth of the rack channel until the rack bar has passed to the limit of its movement with relation to the rack channel.

A ball bearing 12 is preferably provided upon the shaft 13 of the worm to provide for a free movement of the worm, the extremity 110

of said shaft being squared as shown at 14 for the reception of the socket of the usual handle by means of which the worm may be operated.

- 5 The channel rack is normally held in the lowered position, against movement by the upward movement of the rack bar, by means of the spring pressed plunger 15 which is mounted within the boss 16 formed upon the 10 housing, a cap 17 being screw threaded upon said boss and containing the spring 18, the inner extremity of the plunger being tapered as shown at 19 and normally seated in the aperture 20 in the channel rack 4.
- 15 The aperture 20 communicates with a vertical groove 21 in the channel rack 4, said groove terminating at its upper end in the shoulder 22. The rack bar 6 is provided with a lug 23 having a tapered portion 24 at 20 its upper end, said lug being slidably received within the groove 21 and arranged to engage the tapered end of the plunger 15 when the bar 6 reaches the upper limit of its movement with relation to the channel 25 member 4, moving the plunger out of engagement with the member 4, the lug 23 engaging the shoulder 22 in the channel member, causing the channel member to be moved with the bar 6 until the teeth of the 30 channel member are brought into engagement with the pinion 7.

A locking key 25 is slidably mounted in the passage 26 provided near the upper end of the channel member, a leaf spring 27 carried by said channel member normally holding said locking key in engagement with the rear face of the rack bar 6. Ears 28 are provided upon the rear end of the locking key and are normally located in the inclined 40 grooves 29, provided in the upper portion of the housing 1, when the channel member is in the lowered position.

As the channel member is picked up by the rack bar, as above described, and moved 45 upwardly therewith, the key 25, riding in the inclined grooves 29, will be moved into the notch 30 formed in the rear face of the rack bar near the lower end thereof, the spring 27 holding the locking key in this 50 position as the channel member 4 is raised above the housing 1, thus locking the rack bar and rack channel together.

A head 31 provided with a corrugated or 55 serrated upper surface 32, is loosely mounted upon the shank 33 at the upper end of the rack bar 6 by means of a pin 34, this head being provided for engagement with the under surface of the automobile axle or other part of the automobile beneath which 60 the jack may be conveniently placed for the purpose of raising the automobile.

From the above, it will be evident that by rotation of the worm 10, in the proper direction, the pinion 7 will be rotated in a 65 direction to raise the rack bar 6 to the limit

of its movement with reference to the channel member 4 at which time the channel member will be picked up by the rack bar and raised therewith, the two members of the lifting bar being automatically locked together at this point and the teeth upon the rack channel being brought into engagement with the pinion, which continues to raise the rack channel, and with it the rack bar locked thereto, to the upper limit of movement of the rack channel, thus providing a lifting span substantially double the span ordinarily obtained with a lifting bar formed of a single member. 70

When it is desired to lower the jack, the worm is rotated in the opposite direction, the lifting bar being lowered until the channel member is moved into its lowered position at which time the rack bar is automatically unlocked from the channel member and the teeth upon the rack bar are moved into engagement with the pinion which continues the lowering of the rack bar to the initial position. 80

It will be seen that the plunger 15 forms a positive means for preventing the channel member from being accidentally raised by the upward movement of the rack bar until the rack bar has reached the upper limit of its relative movement, at which time the 90 plunger 15 is automatically disengaged from the channel member, allowing the channel member to be moved upwardly with the rack bar. 95

I claim:—

1. A lifting jack comprising a standard, a lifting bar vertically movable within the standard and comprising a pair of rack members, lifting means for alternate engagement with each of said rack members 105 for moving one of said rack members independently of the other, a spring pressed plunger within the housing for holding the other rack member against movement until the first rack member has reached the limit 110 of its upward movement with relation to the second rack member, and means for automatically locking said rack members together at this point the lifting means moving both of said rack members after they are 115 locked together.

2. A lifting jack comprising a standard, a lifting bar mounted for vertical movement within the standard and comprising a rack channel and a rack bar mounted for vertical movement therein, a pinion in the standard normally engaging the rack bar, a spring pressed plunger mounted in the standard normally engaging the rack channel to hold the same against movement, means 120 upon the rack bar for disengaging said plunger from the rack channel when the rack bar reaches a predetermined height, means upon the rack bar for engaging the rack channel to move the same into engage- 125

ment with the pinion after the plunger has been released and means for automatically locking the rack bar and rack channel together at this point.

5 3. A lifting jack comprising a standard, a lifting bar mounted for vertical movement within the standard and comprising a rack channel and a rack bar mounted for vertical movement therein, a pinion in the stand-
10 ard normally engaging the rack bar said rack channel provided with a socket near its upper extremity, a shoulder upon the rack channel above said socket, a spring pressed

plunger mounted in the standard and ar-
ranged to be normally seated in said 15 socket, a lug upon the lower portion of the rack bar arranged to engage said plun-
ger to release the same from the rack chan-
nel and to engage said shoulder to lift the 20 rack channel into engagement with the pin-
ion and means for automatically locking the rack bar and the channel together at this point.

In testimony that I claim the above, I have hereunto subscribed my name.

JOHN A. MORRISON.
